(57) CLAIM

The ornamental design for a toothbrush, as shown and described.

DESCRIPTION

FIG. 1 is a front elevation view of a toothbrush showing my new design;

FIG. 2 is a left side elevation view thereof;

FIG. 3 is a back elevation view thereof;

FIG. 4 is a right side elevation view thereof;

FIG. 5 is a top plan view thereof;

FIG. 6 is a bottom plan view thereof;

FIG. 7 is a front perspective view, as viewed from the bottom left side thereof;

FIG. 8 is a back perspective view, as viewed from the bottom right side, thereof;

FIG. 9 is a front elevation view of a toothbrush showing a second embodiment of my new design;

FIG. 10 is a left side elevation view of FIG. 9;

FIG. 11 is a back elevation view thereof;

FIG. 12 is a right side view of FIG. 9;

FIG. 13 is a top plan view of FIG. 9;

FIG. 14 is a bottom plan view of FIG. 9;

FIG. 15 is a front perspective view, as viewed from the bottom left side of FIG. 9; and,

FIG. 16 is a back perspective view, as viewed from the bottom right side of FIG. 9.

The bristle patterns shown in broken lines in FIGS. 9-16 are for illustration purposes only and form no part of the claimed design.

Applicant is claiming another alternate embodiment of the toothbrush of my new design in which the image of the dragon shown on the front of the toothbrush handle and the image of the phoenix shown on the back of the toothbrush handle in FIGS. 1-16 are interchanged in position.
